UNITED STATES PATENT OFFICE.

HERON R. PALMER, OF ERIE, PENNSYLVANIA.

DESIGN FOR A PNEUMATIC TIRE.

46,447.

Specification for Design.

Patented Sept. 22, 1914.

Application filed February 21, 1914. Serial No. 820,365. Term of patent 7 years.

To all whom it may concern:

Be it known that I, HERON R. PALMER, a citizen of the United States, residing at the city of Erie, in the county of Erie and State of Pennsylvania, have invented a new, original, and ornamental Design for a Pneumatic Tire, of which the following is the specification, reference being had to the accompanying drawings, forming part thereof.

Figure 1, is a plan view of a section of a pneumatic tire, showing my new design.

Fig. 2, is a cross section of the same, on the line $x-x$ in Fig. 1, looking in the direction of the arrow.

I claim:

The ornamental design for a pneumatic tire, as shown.

HERON R. PALMER.

Witnesses:

C. C. STRICKLAND,
E. E. MYERS.
